UNITED STATES PATENT OFFICE

1,996,479

CHAIR SEAT

David A. McCowan, Toronto, Ontario, Canada

Application December 12, 1931, Serial No. 580,621

1 Claim. (Cl. 155—187)

The principal objects of the invention are to provide a chair seat particularly adaptable for use in office or factory chairs or others which may be subjected to rough usage, and to devise a seat 5 of strong, light, resilient material which will present a uniformly smooth surface at all times and which may be produced at low cost.

Further, an important object is to produce a seat for chairs which will have exceptional wear-resistant qualities, will be quite comfortable to the user and will be free from the possibility of tearing or otherwise injuring the clothing.

The principal feature of the invention consists in the novel formation of a seat surface from a 15 single sheet of material having a flanged edge embedded in a groove formed in a suitable seat frame.

In the drawing, Figure 1 is a plan view of a seat constructed in accordance with this invention.

20 Figure 2 is a cross section taken on the line 2—2 of Figure 1.

Chair seats made of cane or of ply wood are prone to wear and ultimately expose sharp ends of cane or of split or separated veneer which are extremely injurious to clothing and in the case of cane chairs the seats are expensive and with ply wood the manner of fastening the seat is objectionable through the use of raised headed tacks or nails.

30 According to the present invention the chair is manufactured with a seat rim 1 which may be of any desirable design or construction and is provided with an open centre 2.

A narrow groove 3 is cut or otherwise formed in 35 the top surface of the seat frame and the top surface 4 between said groove and the opening 2 is slightly depressed.

A seat element 5 herein shown is formed of a sheet of metal having a downwardly turned flange 6 around its perimeter. This flange is shaped to correspond with the shape of the groove 3 and is adapted to fit snugly therein and is retained securely in position by its tensional contact, no other fastening means being required.

45 The seat element 5 herein shown is covered both sides with a surface covering 7 of rubber material which is preferably placed thereon in a uniform

thickness by a special deposition process. This rubber-coated metal sheet provides a non-slip wear-resisting surface which is highly desirable and as herein shown it is formed with a multiplicity of small ventilating perforations 8 but the seat has considerable flexibility and is very resilient. It is quite smooth and free from any obstructions or the possibility of such. It will therefore be very comfortable to the user and there will be no projections of any kind which could injure the clothing.

5 It will be noted that the rubber covering surrounds the flange 6 and that when the flange is forced into the groove the overlying rubber layer will be placed under compression or tension so 15 that it frictionally engages the groove walls in pressure contact effectively retaining the flange and consequently the seat firmly in the frame without the use of separate and objectionable fastening elements.

20 The invention is very simple but produces a valuable improvement in the art of making chairs.

The chair seat has been described as being preferably formed of sheet metal covered with a deposited coat of rubber, but it must be understood that chair seats may be devised in accordance with the construction described which may be formed of some other desirable, strong, durable, flexible sheet material.

25 What I claim as my invention is:

30 The combination with a chair frame having a groove formed therein, of a sheet metal seat element having a rigid downturned flange fitting in said groove, and a surface covering of rubber extending over the surface of said sheet metal seat 35 element and looped around the lower edge extremity of the flange, said rubber covering secured to said sheet metal surface and flange and engaging the inner and outer wall surfaces of the groove and flange in resilient pressure contact 40 to effectively retain the seat element in place, said rubber element thereby serving in the dual capacity of an insulating surface covering for the metal seat element and as an effective anchoring medium therefore.

45 DAVID A. McCOWAN.
